UNITED STATES PATENT OFFICE.

AUGUSTE PACHE, OF NEW YORK, N. Y.

TIME-CONTROL APPARATUS.

1,076,055.

Specification of Letters Patent. Patented Oct. 21, 1913.

Application filed May 9, 1912. Serial No. 696,063.

To all whom it may concern:

Be it known that I, AUGUSTE PACHE, a subject of Switzerland, and resident of New York, in the county of New York and State of New York, have invented certain new and useful Improvements in Time-Control Apparatus, of which the following is a specification.

This invention relates to certain mechanisms, employed in conjunction with a clock movement, whereby time control is exercised in the automatic operation at set periods, of electric switches, gas cocks, water valves and corresponding devices.

10 The invention includes setting, controlling and releasing mechanism, and means whereby the release becomes operable either at any set period within an hour, or at any set period within a given number of hours, said release 15 causing the power of the ordinary alarm spring to operate the switch, cock or valve.

In the drawings,—Figure 1 is a front view of the apparatus, with the dial removed, showing the release mechanism; Fig. 2 is a 25 front view showing the mechanism for control within a period of sixty minutes; Fig. 3 is a side elevation of the mechanism, also showing connection with a gas cock and electric light switch; Fig. 4 is a partial side 30 elevation of the inclosed apparatus, and Fig. 5 is a front view of the dial plate.

My improvements are applicable to any ordinary, cheap clock movement, with an alarm device, the spring which actuates the alarm hammer, also serving the new functions contemplated by me. To this end the shaft 1, carrying the alarm spring 2, is extended through the back plate 3 of the clock, where it connects with and turns the 35 spindle 4 or other moving member of a valve, as 5, to open or close said valve. Also said moving member 4 has an extension 6, to which is attached a lever arm 7, whereby said moving member may be turned in the 40 act of winding up the spring. A further extension, as 9, may connect with and operate an electric light switch, as 10. I provide certain automatic means to release the alarm spring at a predetermined time, said 45 means including a cam 11, having a notch 12; said cam being carried by the central, or main, clock-shaft 13, which also carries the pointer or hand 14, said hand 14 thus making a complete traverse of the dial 15 with 50 each revolution of shaft 13. The arbitrary

arrangement of dial 15 which I have devised provides divisions for 60 minutes in its circumference, the reading of said minutes being from right to left, or opposite to the direction of travel of the hand. I also divide said minute divisions into four parts, providing in the whole circumference of the dial 240 divisions of 15 seconds each. The cam 11, in its rotation, presents its notch 12 to the nose 16 of a pawl 17, that is pivoted 60 at 18 to the clock frame, whereby said nose 16 enters said notch once in each revolution of said cam, in this act the upstanding arm 19 of pawl 17, releasing a finger 20 which extends from the alarm shaft 21 to a point 65 in the path of finger 20. Under such release action the alarm hammer vibrates, and the spring shaft 1 turns in the act of operating the valve, switch or cock with which it is connected.

75 The mechanism thus far described in conjunction with the usual clock mechanism, is sufficient for the utilization of the device when it is desired to set it, say for example to operate after a lapse of 10 minutes; the 80 hand 14 is set to point at the numeral 10 on the dial, and said hand being in fixed alignment with notch 12, will register at zero, or 60, when the nose of pawl 17 falls into said notch thereby releasing the alarm and actuating spring.

75 Additional mechanism, required to increase the period of inaction beyond one hour is as follows: I provide a gear wheel 90 22, whose pivot 23, which carries an hour pointer or hand 24, supports it above the cam 11, said cam having a spur 25, meshing with said gear and turning it the space of one tooth with each revolution of said cam. In the arbitrary arrangement shown, the 95 gear 22 has 30 teeth, and hand 24 points to a corresponding dial arrangement 26, whose thirty divisions, each representing one hour read from right to left. A pivotal pawl 27 is held by spring 28 normally engaged with 100 gear 22, to steady the latter, the pawl 27 riding out of engagement with a tooth into engagement with the next succeeding tooth with the step by step rotation of said gear. The gear 22 carries a stud 29 in the radial 105 line of hand 24, said stud contacting with an arm 30 of a two arm lever, which is pivoted at 31, and whose other arm 32 terminates in a pawl 33. Obviously the hand 24 can be set with respect to dial 26 so that stud 110

29 may be a given number of teeth or hours away from contact with arm 30. The pawl 33 rides upon the periphery of a cam 34, which cam is pivoted at 35, and has a handle 36 by which it may be swung and adjusted about its pivot. A spring 37 holds said cam in its normally inoperative position, and returns it to said position when released. Said cam has a peripheral notch 38 to receive pawl 33 when said cam is swung, by its handle about its pivot, in this act the forward shoulder 39 of the cam meeting the finger 20 of the alarm and control movement, and preventing release of said movement. In this restrained position of the parts the cam 11 may rotate freely without releasing the alarm spring, and it is not until the stud 29 meets and moves the arm 30 that the pawl 33 leaves notch 38 and allows cam 34 to be retracted by its spring. When so retracted, then the 60 minute cam comes into operation. Hence, as an example the hand 24 may be set at its dial numeral 5, and the hand 14 set at its dial numeral 30, the cam 34 at the same time being swung over to engagement with pawl 33. As a result of this setting the alarm spring will be released at the lapse of $5\frac{1}{2}$ hours. If it be desired to release cam 34 at an earlier period, for a new setting, then the spring push piece 40 should be pressed inwardly causing it to shift pawl 33 out of engagement with notch 38, having the desired result.

As a means for setting the hands 14 and 24, I provide a rod 41, terminating at its upper end in a knurled head 42, and having a bevel gear 43 at its lower end, said gear

meshing with a bevel gear 44 on shaft 13, which may be rotated thereby.

Various applications of the power of the alarm spring, controlled as described, will occur to the user, whether such uses be in control of fluid valves or cocks or electrical switches, for cooking, light, heat or power, and whether in turning on the supply or in shutting it off.

I claim:

An alarm clock having an alarm spring shaft, a control device operated by said shaft, a cam on the center clock shaft, said cam having a notch, a pawl adapted to enter said notch, an arm extending from said pawl, and a finger upon the alarm hammer shaft in the path of said arm, together with a gear wheel carrying a pointer, a spur upon said cam adapted to mesh with said gear to move it the space of one tooth with each revolution, a stud upon said gear wheel, a two armed pivotal lever, one arm thereof in the path of said stud, a pivotal cam having a shoulder to restrain the alarm spring, a notch in said pivotal cam to receive a pawl on the other arm of the pivotal lever and means for setting said gear wheel whereby through the aforesaid instrumentalities the alarm spring is released at a predetermined point in the rotation of the gear wheel.

Signed at New York city in the county of New York and State of New York this 30th day of April A. D. 1912.

AUGUSTE PACHE.
